UNITED STATES PATENT OFFICE

JAMES J. MORRISON, OF WORCESTER, MASSACHUSETTS, ASSIGNOR TO THE AMERICAN STEEL AND WIRE COMPANY OF NEW JERSEY, A CORPORATION OF NEW JERSEY

ELECTRIC CABLE

Application filed August 6, 1928. Serial No. 297,760.

This invention relates to the manufacture of electric cables and consists of a construction whereby a cable of superior quality is produced. The invention concerns particularly cables whose conductor or conductors are wrapped with paper or other insulating fabric, such as cambric, the assembled insulated conductor or conductors being impregnated and saturated with insulating compound 10 pound which may be an oil or similar material, and with a lead sheath overall.

Such types of cables present difficulties in saturation, due to the tightness and thickness of wrapping of insulating tapes of paper or other material, in removing both air and moisture and in securing thorough and even saturation.

After installation, as the cables are alternately heated and cooled, the saturating oil expands and contracts and, in so doing, flows into or out of reservoirs provided for such purpose. The restriction offered to this flow by ordinary insulation often results in high pressures being developed within the cable.

The object of my invention is to provide a construction of cable which will be more evenly and uniformly saturated when manufactured, and which will maintain such saturation more uniformly after installation 30 when the cable is connected with such oil supply reservoirs.

These results are secured by perforating the tapes of which the insulation is formed prior to their application to the conductor or 35 conductors in the manner shown by the drawings submitted herewith, but it is not intended that any particular form or arrangement of the perforations in the tapes be specified.

In the drawings—

Figure 1 is a plan of one end of a single conductor cable, partly broken away to show the several elements.

Figure 2 is a cross-sectional view taken on the line II—II of Figure 1.

Figure 3 is a plan of one end of a multiple round conductor cable, partly broken away to show the several elements.

Figure 4 is a cross-sectional view taken on the line IV—IV of Figure 3.

Figure 5 is a plan of one end of a three-con-

ductor sector-type cable, partly broken away to show the several elements.

Figure 6 is a cross-sectional view taken on the line VI—VI of Figure 5.

Referring more particularly to the drawings, the numeral 1 designates the conductor or conductors with insulation 2 in the form of tapes applied helically, these tapes being perforated, as at 3. Over the insulation of the individual conductor and assembled conductors is shown a perforated metallic tape 4 and 4^a, respectively, and a lead sheath 5. In the multiple conductor cables of Figures 3 to 6, the spaces between the assembled conductors are filled with bodies of filling material, such as hemp.

By the application of perforated tapes, as shown, or by tapes perforated in any other form, a body of insulation will be obtained containing a very great number of small reservoirs which will materially assist in the impregnation of the insulation during the saturating process to secure uniform impregnation, and which will result in an increased proportion of insulating compound in the body of the insulation.

Such saturating process may be performed at a relatively lower temperature to avoid deterioration of paper during evacuation and drying; and to lessen deterioration of the compound during the impregnation, as the apertures in the insulation formed by the perforations facilitate removal of air and moisture for a given vacuum and, in a similar manner during the saturating process, permit the ready ingress of the saturant.

Where presaturated paper, varnished cambric, treated paper or other fabric tape insulation is employed, the use of the perforated tapes permit of evacuation, drying and impregnating in the same manner as cable insulated with untreated paper.

By the use of such perforations a cable constructed of treated paper and other type of paper insulation will permit of impregnation in the usual manner.

Perforated metal tape or tapes to serve as conductors may be used on any of the above constructions at any point or points of the insulation between conductor or conductors

and sheath, since the perforations permit the saturant to pass readily therethrough.

In any such construction of cable, the respective tapes may be perforated either in whole or in part to give any combination of 5 perforated and unperforated tapes, and the respective tapes may be applied in such manner that adjacent convolutions overlap, or abut; or they may have open spaces between.

10 The use of perforated tapes in construction of the cable insulation will be particularly applicable where hollow core conductor, sheath oil channel construction or combination of these methods are employed in 15 order to permit of drying, impregnation or reimpregnation during and after installation.

10 During operation in service, cable of such construction will be assisted materially in the 20 maintenance of a uniform impregnation where reservoirs are used for supplying oil to the cable, due to the porous character of the perforated insulation and pressures generated within the cable, will more readily 25 equalize themselves throughout the length of the cable, thus preventing local high pressure spots.

Throughout the specification and claims 30 the term "fabric", describing the insulating tape, is meant to include paper and paper compositions, treated or untreated, textile tapes of any kind, and any combination of 35 paper and textile products made into tape form and usable as an insulating material.

35 While I have shown and described certain specific embodiments of my invention it will be understood that I do not wish to be limited thereto since various modifications may be made without departing from the scope 40 thereof, as defined in the appended claims.

I claim—

45 1. In an electric cable, the combination of at least one conductor, an insulation surrounding said cable composed of at least one layer of perforated fabric, and a perforated metal tape overlying said layer of fabric, said perforations in said tapes facilitating the 50 impregnating of said insulation with fluid insulating compounds.

55 2. In an electric cable, the combination of at least one conductor, an insulation surrounding said cable composed of a plurality of layers of fabric tapes, at least some of said tapes being perforated, and at least one layer of perforated metal tape overlying said 60 fabric tape, said perforations in said tapes facilitating the impregnating of said insulation with fluid insulating compounds.

65 3. In an electric cable, a plurality of conductors, each of said conductors being provided with an insulation composed of a plurality of layers of fabric tapes, at least some of said tapes being perforated, a perforated metal tape overlying said fabric tapes on 70 each of said conductors, and a perforated

tape surrounding and binding all of said insulated conductors together, said perforations in said tapes facilitating the impregnating of said insulation with fluid insulating compounds.

75 4. In an electric cable, a plurality of conductors, each of said conductors being provided with an insulation composed of a plurality of layers of perforated paper tapes, a perforated metal tape overlying said paper tapes on each of said conductors, and a perforated tape surrounding and binding all of 80 said insulated conductors together, said perforations in said tapes facilitating the impregnating of said insulation with fluid insulating compounds.

85 5. In a multiple-conductor cable the combination of a plurality of individually insulated metal enveloped conductors cabled within a sheath with filler spaces between, the metal envelope of each insulated conductor being perforated so as to be penetrable by liquid insulating material, and the insulation immediately surrounding each conductor and within the metal envelope consisting of 90 perforated permeable material filled with liquid insulating material, and a flood of liquid under pressure maintained within the filler spaces and said perforations in said metal envelopes and said insulation.

95 In testimony whereof, I have hereunto set my hand.

JAMES J. MORRISON.
